ELECTRIC PHONOGRAPH

Norman L. Chalfin, New York, N. Y., assignor of
thirty per cent to Irving Seidman, New York,
N. Y.

Application May 24, 1950, Serial No. 163,934

2 Claims. (Cl. 179—100.4)

1

This invention relates to improved electric circuits for sound reproducing amplifiers which may be attached to existing radio or radio-phonograph equipment or built into new phonograph equipment.

It is common, in phonograph record players at present in use that when the current is turned on to start the turntable rotating motor and energize the amplifying tubes which form parts of the apparatus, to encounter a delayed period of time, between the starting of the motor and the full operation of the vacuum tubes. This delay is due to the fact that the indirectly heated cathodes of the tubes normally used require time to heat up and reach an operating temperature.

It is the purpose of this invention to provide an apparatus wherein the circuits and parts are so arranged and electrically connected that the tubes are instantly heated to the desired operating temperature. In other words, the starting of the motor and the heating of the tubes to the required operating temperature are substantially simultaneous with the turning on of the current supply.

The best embodiment of the invention has been chosen for illustrative purposes, but this embodiment should be viewed as being illustrative only and not as limiting because obviously the invention is capable of other embodiments having revised details of construction, so long as they fall within the ambit of the appended claims.

The invention itself, however, both as to its organization and its method of operation, will best be understood from the following description of a specific embodiment when read in connection with the accompanying drawing, in which:

Fig. 1 is a diagram showing a circuit hook up with a radio-phonograph self acting switch and quick heating phonograph amplifier.

Fig. 2 is a circuit diagram showing a phonograph unit employing quick heating vacuum tubes.

Fig. 3 is a circuit diagram showing a carbon pick up in the circuit, and

Fig. 4 shows in diagram, an amplifier with a double button carbon microphone.

An example of the application of this invention is illustrated in Fig. 1 which shows a phonograph pick up preamplifier which can be attached to existing radio equipment or built into radio phonograph combinations. The preamplifier is so constructed that when the motor starts

2

ing switch of a phonograph record changing or single record playing equipment is closed, the preamplifier is instantly ready for operation and simultaneously switches the preamplifier output into electrical connection with a radio unit.

Referring in detail to the parts, and particularly to Fig. 1, numeral 11 designates a normally closed switch which is held in its open position by the weight of a pick up mechanism 12 engageable with a record disk upon a turntable (not shown). A motor 13 is connected between a power line 14 and the normally closed switch 11. The primary coil 15 of a transformer 16 has connection with the power line 14 and the line 17, through the switch 11 when same is closed. A switch 18 is provided in the line 14 as alternative to switch 11. The secondary coil 19 of the transformer 16 leads through the line 20 to a ground connection which is the negative side of the D. C. line. The positive branch of the D. C. is obtained through chemical rectifier 26 and supplies D. C. power to the plates and filaments of preamplifier 21. The negative or ground return of the D. C. is made through the series connected filaments of tubes 30 and 31 to ground terminal connection 22. Ground terminal connection 22 is common with ground terminal connection 45. A line 24 connects the pick up unit with the preamplifier 21. The ground terminal of pickup 12 is connected to ground terminal 22 through lead 23. A relay 24' is connected, in series with the filaments of tubes 30 and 31. A line 28 leads from the output circuit of a radio (not shown) and line 29 to a power amplifier (not shown). The amplifier tubes 30 and 31 heat very quickly (in less than three seconds). This type of tube is generally known as the filamentary cathode type and is constructed with filaments that will heat almost instantaneously, to a temperature, sufficiently high to emit electrons, thus rendering the tube fully operative when a record is started revolving.

The operation of the system will best be understood when read in conjunction with the diagram shown in Fig. 1. With the switch 18 (if used) and the pick up switch 11 closed, power is simultaneously transmitted to the motor 13 of the sound record playing apparatus and the primary coil 15 of the power isolation transformer 16 inducing a like voltage in the secondary coil 19. The secondary voltage is applied to the chemical type rectifier 26 and filter system which delivers D. C. along line 25 for both plate and filaments of the tubes 30 and 31. The relay 24' and a voltage dropping resistance 32

is disposed in the filament circuit 27. When the power is applied, the filaments of the tubes 30 and 31, which are of the instant heating filamentary types, are supplied with the proper voltage. The current, which the filaments draw energizes the relay 24'. The said relay, in its de-energized condition normally has its contacts 40 and 41 closed. When energized, however, contact 40 is drawn over to close contact point 42 and open the contact at 41. Attached to contact 40 is the input of the power amplifier, while attached to contact 41 is the audio output circuit of the radio detector.

The output of the phonograph pick-up preamplifier 43 is attached to the contact point 42 through capacitor 44. The return circuits of both preamplifier and radio are through the shield grounds 45 which are bonded together. The preamplifier input 46 connects with the pick up unit 12 through the line 24.

The diagram illustrated in Fig. 2 shows an instant heating phonograph record playing system particularly suited for a child's use. The action of lifting the phonograph pick up arm 12' allows switch contact 11' to close, thus energizing rectifier 28', supplying D. C. plate and filament power to the amplifier tube T. The tube T being of the filamentary type is immediately ready to reproduce the energy picked up from the sound record by the pick up unit.

A third example of the application of this invention is illustrated in Fig. 3 wherein sound record reproduction is accomplished without vacuum tubes. A bridge circuit is employed to cancel out the D. C. component in the high impedance voice coil 50 of a speaker unit 51. The bridge comprises buttons 52 and 53 of the double button carbon pick up as one pair of arms and the resistance arms 54 and 55 as the other pair. When current through a circuit comprising button A, resistance 54 and voice coil 50 in one direction equals the current flow through resistance 54, button B and voice coil 50 in the opposite direction, the net current in the voice coil 50 will be zero. The application of the invention to this circuit is the switch on system and chemical rectifier combination in which lifting the arm from a rest, places the apparatus in instant operation. A like result may be accomplished with the use of batteries B-B' as an alternative source of power, as shown in Fig. 4.

In the Fig. 4 instance, however, the switch 56 must be of the double pole single throw type. The batteries B-B' are of equal potential and are connected in series. The junction of the two batteries is connected to the central (common) connection of the double button pick up unit.

If the pick up unit D. B. P. should be a double carbon button microphone instead of a phonograph pick up, a public address system is possible in which the instantaneous operational readiness is available, actuated by a double pole normally open-press-to-use type of switch.

I claim:

1. In an electric phonograph record player pre-amplifier system, the combination of: a multi-stage, direct-heater vacuum-tube amplifier, the tubes of said amplifier being coupled in cascade

relation, the heaters of said amplifier tubes being connected in a series circuit; a relay, having a coil and at least single-pole-double-throw contact terminals, said contact terminals being connected between the output circuit of said amplifier and a utilization circuit for transferring said output circuit to said utilization circuit, in place of some other circuit, that may be connected to said utilization circuit through said relay contacts, when said relay is energized; the said relay coil being connected in series with said heater circuit; a semi-conductor rectifier supply for energizing said amplifier tubes and said heater circuit; a motor and turntable means; a normally-open-on-pressure switch coupled between a source of electrical power and said motor and said rectifier supply for applying said power to said motor and said rectifier supply when said pressure on said switch is relieved; and a phonograph pickup arm assembly electrically coupled to the input of said amplifier and engageable with said pressure switch whereby movement of said pickup arm into its record playing position relieves said pressure on said switch to energize said motor and said amplifier and said filament circuit to render said amplifier operative and to energize said relay.

2. In an electric phonograph record player, the combination of: a vacuum tube amplifier, said amplifier being capable of substantially instantaneous energization upon application of power thereto; an instantaneously energizable rectifier means coupled to said amplifier means for energizing said amplifier means; electric motor and turntable means; pressure switch means for connecting said rectifier means and said motor means to a source of electric power; and a phonograph pickup arm means coupled to said amplifier and engageable at a rest position with said pressure switch means to maintain the record player inoperative, and engageable with a disk in its use position on the turntable of said motor for reproducing the sound recording on said disk, said motor and said amplifier being rendered operative when said pickup arm means is moved from its rest position to its use position.
